HEEL FINISHING MACHINE

Henry B. Greenough, Beverly, Mass., assignor to
 United Shoe Machinery Corporation, Paterson,
 N. J., a corporation of New Jersey

Application January 5, 1934, Serial No. 705,417

26 Claims. (Cl. 12—49)

This invention relates to finishing machines and is herein illustrated as embodied in a heel-finishing machine of the type disclosed in Letters Patent of the United States No. 1,943,308, granted January 16, 1934, upon an application filed in the name of Henry B. Greenough.

It is customary in finishing heels of many types of shoes to decorate their peripheral surfaces by forming thereabout rows of indentations, which rows are parallel in each case to the rand crease and which usually terminate at opposite sides of the heel near the breast corners. As the angle of a heel surface to be thus indented with respect to the tread surface varies not only in different shoes but also at different points about the periphery of the heel of practically any shoe, it is apparent that if uniformity in the length of the indentations at all parts of the heel is to be obtained, the relative positions of the indenting tool and the heel must be varied as the point of operation of the tool on the heel is transferred thereabout.

Heretofore such relative positioning of the tool and the work, especially in connection with the indenting of heels as distinguished from the indenting of a sole margin or welt, for example, has been effected by the operator's varying the position of the shoe with respect to the tool so as to effect complete contact heightwise of the shoe between it and the tool. Accordingly the uniformity of the indenting operation varied appreciably and depended to a great extent on the ability of the operator, his state of fatigue and the attention given to his work.

In view of the foregoing a general object of the invention is to improve and expedite the indenting operation by rendering the tool self-positioning. To this end the invention contemplates the provision, in a heel-finishing machine, of an indenting tool mounted for bodily swinging movement, and means mounted to engage a part of the surface to be indented for controlling the swinging movement of the tool to effect complete contact between the operative face of the tool at the operating point and the heel surface.

While swinging movement of the indenting tool could occur about an axis disposed between the tool and the positioning means, in the illustrated construction it occurs about a tangent to the operating surface of the tool at the operating point as an axis and, accordingly, the pressure of the work against it is ineffectual to alter its position. However, in accordance with another feature of the invention, means is provided, in combination with the tool and posi-

tioning means referred to above, for yieldingly urging the tool toward one extreme of its swinging movement. Now, as a result of presenting the heel surface to be indented to the tool and the positioning means, the latter, against which the heel surface is held, is actuated by the movement of the heel surface into engagement with the tool and causes the indenting wheel to be so positioned as to have complete contact with the heel as described above. In most instances peripheral heel surfaces are substantially straight heightwise thereof but they may also be curved, as in the case of the heels of some women's shoes which are indented. It is therefore to be understood that the invention comprehends any arrangement of a tool and positioning means or guide the operative surface of which is substantially intersected by the operative surface of the tool when extended.

The features of the invention as described above have application not only in connection with machines to which the work is presented by the operator, but also the machines in which the work is held and presented to tools mechanically as by a jack, for example.

Invention is to be recognized, therefore, in the provision, in a finishing machine, of the combination of an indenting tool and means for jacking a shoe, the tool and jacking means being relatively movable to allow the point of operation of the tool on the heel to be transferred thereabout. It will now be apparent that whether a shoe is manually or mechanically presented to a tool which is self-positioning, in accordance with the above features of the invention, complete heightwise contact between the surface to be indented and the tool at the operating point is assured.

The row of indentations applied to a heel as a result of the indenting operation is generally made near that edge of the heel which is adjacent to the upper and on a section of the heel known as the rand. As every heel does not comprise a rand, strictly speaking, it is to be understood that the term "rand" as used herein is applied to the uppermost section of a heel adjacent to the upper to which indentations are commonly applied and which forms a lower boundary of the gap between the heel and adjacent portion of the upper, which gap is commonly known as the rand crease. Frequently the marginal portion of the heel which bounds the rand crease is beveled slightly for decorative purposes, this beveled surface as well as the peripheral surface of the heel being burnished in the finished shoe. It is apparent that the

proper relative heightwise position of either a rand-burnishing or indenting tool and the heel to be operated upon is essential in order to insure that the rand will be well burnished without injuring the upper, or that the row of indentations shall be applied about the periphery of the heel at all points equidistant from the rand crease. Accordingly, it is another important object of the invention to insure that the movement of the point of operation of such a tool about the heel shall occur in a plane which is predetermined definitely with respect to the rand or the rand crease. To this end, there is provided, in combination with a tool for operating upon the rand of a heel, improved shoe-jacking means by the use of which a shoe can be jacked in a position which is predetermined heightwise with reference to the actual part of the shoe which is to be operated upon. In the illustrated machine, this jacking means comprises shoe-positioning members shaped and arranged to engage the shoe within the rand crease adjacent to the heel at opposite sides thereof, the rand-engaging surfaces of the members and the operating surface of said tool being disposed at the same height or in predetermined heightwise relation to each other. The jacking means also comprises cooperating clamping members for applying jacking pressure to the heel part of the shoe.

These and other features of the invention will appear more fully from the following description when read in connection with the accompanying drawings and will be pointed out in the appended claims.

35 In the drawings,

Fig. 1 illustrates in side elevation a part of a machine in which the present invention is illustrated as embodied;

Fig. 2 is a sectional plan view with parts broken away, the section being taken along the line II--II in the work jack illustrated in Fig. 1;

Fig. 3 illustrates the work jack after being rotated through ninety degrees from its position illustrated in Fig. 1, the toe of the shoe indicated in this view being pointed toward the observer;

Fig. 4 is a plan view of the shoe-positioning instrumentalities illustrated in Figs. 1 and 3;

Fig. 5 is a side elevation of the indenting and rand-burnishing devices in operative relation with respect to a heel the periphery of which is substantially straight heightwise;

Fig. 6 is an end elevation of a part of the indenting mechanism shown in Fig. 5 with parts broken away;

Fig. 7 is a sectional plan view taken along the line VII--VII of Fig. 6;

Fig. 8 is a plan view of the mechanism illustrated in Fig. 6; and

Fig. 9 is a sectional elevation taken along the line IX--IX of the structure illustrated in Fig. 8.

With reference to Fig. 1 of the drawings, at the center of a frame 14 (this member as illustrated in the Letters Patent referred to above has the same reference character) is rotatably mounted a jack carrier 16 and a spider 18 (the corresponding parts in the machine illustrated in the aforesaid Letters Patent are designated by the numerals 20 and 22 respectively), the jack carrier and spider each having the same number of arms 24 provided with shoe-jacking instrumentalities at their ends. The jack carrier 16 and spider 18 are rotatably mounted so as to carry the shoes clamped therebetween progressively to various operating stations, of which the indenting and rand-burnishing station illustrated herein may be

one, and also to cause the sides of the heels to be moved relatively to the tools to cause the sides of the heels to be operated upon. Between the last-mentioned movements the carrier 16 and spider 18 remain stationary while the work is rotated about the axis of the jack to cause the rear-most portion of the heel to be presented to the operating tools.

In the illustrated construction, a shoe 20 the heel of which is to be indented and burnished along the rand is clamped between opposite arms of the spider 18 and jack carrier 16 by an abutment 22 adapted to engage the tread surface of the heel and a clamping member 24 shaped to engage the top of the heel part of the last. The clamping member 24 is constituted by a U-shaped slide mounted for vertical movement with respect to a spindle 26 in slideways formed at each side of the head of the spindle. A helical spring 27 normally holds the clamping member 24 in its extreme upper position, which is determined by a screw 29 extending between the arms of the clamping member 24 and adapted to engage the lower end of the head of the jack spindle 26 (the corresponding part as disclosed in the aforesaid Letters Patent being designated 48). The abutment 22 is carried by a shaft 28 which is rotatably mounted in the spider 18 coaxially with the jack spindle 26, which also is rotatably mounted in the jack carrier 16 and which is rotated in the manner referred to above by a gear train 30, as described in the aforesaid Letters Patent.

The operating tools in the illustrated embodiment of the invention comprise an indenting tool 32 and an oscillating rand burnishing tool 34 which are carried by a frame 36 in which is rotatably mounted a drive shaft 38 for operating the burnishing tool. The frame 36 and associated parts are yieldingly supported by an H-shaped link 39 which is pivotally mounted on a block 40 and which is supported by a spring 41. The block is mounted for heightwise adjustment on an arm 42 (this member being designated in the aforesaid Letters Patent by the numeral 40). As in my prior machine, the arm 42 at its lower end (not shown) is pivotally mounted on the frame 14 so as to allow the tool to be moved into and out of engagement with a shoe carried by the jack. Similarly, as in my prior construction, the drive shaft 38 is rotatably mounted near the base of the arm 42 so as to allow angular movement between the shaft 38 and the arm 42. The arm 42 is normally urged toward the center of the machine to cause the tool to be held against the heel by means of a spring 44 which, by means of eye bolts, is connected to the arm 42 and the frame 14; and the arm 42 is moved to carry the operating tools away from the shoe when it is desired to move the shoes between stations by a bell-crank-operated link 46 which is pivoted to an extension 48 of the arm 42, the parts corresponding to which in the machine of the aforesaid Letters Patent will be readily distinguished by reference thereto.

As pointed out above, in holding a shoe for a rand-burnishing and heel-indenting operation, it is desirable that the rand crease or rand itself should be positioned heightwise definitely with respect to the rand-burnishing tool, and preferably at practically the same height. To this end, the invention contemplates the positioning of a shoe with reference to the rand or rand crease itself so that variations in the height of heels will not affect the proper heightwise positioning of the rand crease or rand with respect to the

operating tools. This end is attained in the illustrated construction by positioning the shoe in the desired position before applying any jacking pressure, and then jacking the shoe without moving it from its fixed position. The shoe 20 is herein illustrated as being thus positioned by rand-crease-entering fingers 50 and 52 which are mounted respectively on pivots 54 and 56 carried by a support 58. The fingers 50 and 52 have coating arms 60 and 62, respectively, which are connected by a stud 64 so as to cause the ends of the fingers 50 and 52 always to be equally spaced from the center of the jack. The fingers 50 and 52 are connected by a spring 66 which urges them toward each other. As illustrated in Fig. 3, the ends of the fingers 50 and 52 are shaped to enter the rand crease of a shoe and have rand-engaging surfaces 68 and 70, respectively, which position the heel part of the shoe heightwise. Moreover, as will readily be understood by reference to Fig. 3, the ends of the fingers 50 and 52, when yieldingly engaged within the rand crease, also position the heel part of the shoe laterally of the axis of the jack.

Provision now having been made for positioning the heel part of the shoe laterally and heightwise with reference to the rand crease adjacent to the breast corners of the heel, another abutment 72 adapted to position the plane of the rand crease by limiting movement of the forepart of the shoe about the fingers 50 and 52 as fulcrum is adjustably mounted on the outer end of the support 58 on a screw 74 which extends through a slot in the abutment 72, thereby allowing the latter to be adjusted heightwise. As indicated in Fig. 1, the abutment 72 is shaped and positioned so as to be engaged by the tread surface of the forepart of the shoe, the relation between which and the rand crease varies so little in shoes of the same class as to be practically negligible so far as allowing variation in the position of the rand crease of the shoe is concerned, and which, even in shoes of different types, does not vary a great deal. Further to facilitate positioning a shoe centrally in the jack before the jacking pressure is applied, the fingers 50 and 52 are provided with heel-breast-engaging members 76 and 78 which are so spaced as normally to engage the breast of the heel adjacent to the corners whereby the longitudinal axis of the forepart is substantially aligned with the abutment 72 as a result of the heel being held firmly against the members 76 and 78.

The support 58 has a hollow shank 80 on the upper end of which is threaded a nut 82 which, when made up against the upper end of a sleeve 84 surrounding the shank 80, holds the lower end of the sleeve 84 firmly against a shoulder at the lower end of the shank 80. The sleeve 84 is rotatably mounted in a bearing bushing 86 carried by the arm 18 of the spider and is held against upward movement owing to jacking pressure by means of a ball thrust bearing 88. The shaft 28 referred to above which carries the abutment 22 is mounted for adjustment axially within the shank 80 and is splined thereto by means of a key 90.

Heightwise adjustment of the shaft 28 is effected by an adjusting nut 92 threaded on the upper end of the shank 80, the upper end of which nut 92 rotates freely between opposed shoulders on the shaft 28 constituted by washers 94 which are held in assembled relation on the end of the shaft 28 by means of a nut 96. By means of the construction above described, heightwise adjust-

ment of the abutment 22 of appreciable range is made possible. However, to facilitate bringing the abutment 22 into intimate contact with the tread surface of the heel of a shoe previously positioned as above described, other means which will now be described is provided.

To the abutment 22 are attached three studs 98 which are slidably received in a plate 100 formed integral with the shaft 28. Helical springs 102 surround the studs 98 and cause the abutment 22 normally to be urged toward the plate 100. The adjustment of the abutment 22 with respect to the plate 100 is effected by means of a wedge 104 arranged to slide therebetween, the upper surface of which wedge is inclined with respect to the lower, is serrated and engages a similarly serrated and inclined surface at the lower side of the plate 100. The serrated surfaces of the wedge 104 and the plate 100 cooperate to insure that the wedge 104 will be held releasably in whatever position to which it is moved by the operator and at the same time allow the wedge to be readily moved back and forth. As illustrated in Fig. 2, the wedge 104 is disposed between two of the studs 98 and has a slot 106 through which the third stud 98 extends. The studs 98 form a slideway for the wedge 104, the latter being yieldingly urged toward one extreme of its limited movement by a light spring 108 one end of which bears against that stud 98 which extends through the recess 106.

To an extension 110 on the forward end of the support 58 is attached a brace 112 the lower end of which is mounted in a collar 114 which is mounted to rotate with the jack spindle 26 in the end of the arm 18 of the jack carrier.

The jacking of the shoe in the illustrated device is effected by raising the spindle 26 which preferably can be accomplished in the same way as in the machine disclosed in the aforesaid Letters Patent (namely, as a result of the jacking plate 58 being elevated in contact with the lower end of the jack spindle 26 while at the loading station). When the jack spindle is thus elevated, the spring 27 is compressed until the desired clamping pressure is exerted upon the heel part of the shoe. Thereafter, as pressure on the jack spindle 26 is released, the latter is locked in its highest position by means of a spring-actuated dog 116 (corresponding to that part designated by the numeral 52 in the aforesaid Letters Patent).

Referring now to the indenting device, the indenting wheel 32 is carried by a spindle 118 rotatably mounted in a sleeve 120, the latter being threaded into a bearing member 122 so as to provide a vertical adjustment for the indenting wheel 32. The sleeve 120, after having been turned to position the indenting tool heightwise, can be locked by making up a check nut 124, threaded on the sleeve 120, against the top of the bearing member 122. Extending from the bearing member away from the center of the machine is a guide having two arcuate arms 126 the center of curvature of which is substantially at the operative face of the indenting wheel 32 at the operating point. The arms of the guide 126 move freely in a guideway composed of two sets of rolls 128, each set of which provides a four-point bearing, as indicated in Fig. 5, for each of the arms 126. The rolls 128 are rotatably mounted on a U-shaped member 130 the arms of which are received in horizontal grooves in the frame 36 so as to permit adjustment of the indenting wheel 32 toward and away from the axis of the drive shaft 38 and with respect to the position of the

rand burnishing tool 34. The member 130 can be clamped in any desired adjusted position by means of screws 132 and 134 which are threaded in and abut respectively the frame 36. The 5 swinging movement of the bearing member 122 in a clockwise direction (Fig. 5) is limited by a bar 136 connecting the lower ends of the arms 126, the outer ends of which bar 136 are spaced from the sides of recesses in the arms 10 of the member 136. The bearing member 122 also is yieldingly urged toward one extreme position of its limited movement by a spring 138 which extends between the middle of the bar 136 and a pin 140 fixed in the upper end of the frame 36. The 15 bearing member 122 being adjustable about substantially a tangent to the operating surface of the indenting tool 32 at the operating point, pressure of the work against the indenting tool alone is ineffectual to cause any movement of the bearing member 122 away from its extreme position and against the tension of the spring 138. However, the indenting wheel 32 is so positioned as to have complete heightwise contact at the operating point with the heel surface presented thereto 20 by means of a guide in the form of a roll 142 having a cylindrical face, as illustrated in Figs. 5 and 6, or a curved face, as illustrated in Fig. 1, and which is mounted to rotate freely on the sleeve 128 as a journal. Therefore, as will be more 25 fully described later, as the indenting wheel is brought into engagement with the heel surface to be indented, the roll 142 first engages the heel surface and causes the indenting wheel 32 to be swung into the desired angular relation with respect to the heel surface. The indenting tool 32 and roll 142, as illustrated in Figs. 5, 6 and 8, are shaped and arranged to operate upon a heel the peripheral surface of which is substantially straight heightwise thereof, but it is to be understood that the shape of the roll and wheel can be 30 modified in accordance with the heightwise contour of the heel to be burnished so that they have the curved form which they are illustrated as having in Fig. 1, for example, whereby they are adapted for operating upon a heel which has a heightwise curvature. In any case, the guide roll 142 and the indenting wheel 32 are so shaped and arranged that the element of the periphery of the indenting wheel at the operating point, when 35 extended, intersects the work-engaging surface of the roll 142, thereby insuring complete heightwise contact between the wheel and the heel surface to be indented when both the wheel and the guide are in contact with the heel surface.

40 55 The rand-burnishing tool 34 has a lip 144 shaped to be inserted in the rand crease and having a burnishing surface which may be beveled if desired and adapted to engage the margin of the rand. The tool 34 is attached to the ends of an oscillating yoke 146 which is pivoted to the frame 36 on a stud 148. The sides of the yoke 146 slidably embrace a block 150 to which is imparted a circular movement by an eccentric 152 formed on the upper end of a sleeve 154 which is splined to the shaft 38 by means of a key 156. It is apparent that as the drive shaft 38 is rotated only those components of the motion of the eccentric 152 which extend concentrically with respect to the stud 148 impart any 60 movement to the yoke 146 which, therefore, is oscillated as the drive shaft 38 rotates. The sleeve 154 is supported at its lower end by the frame 36 and has a flange 158 below the eccentric 152 for supporting the block 150 and yoke 146. If desired, the tool 34 can be heated 65

by a flame from a gas pipe 160 carried by a pair of studs 162 one of which is attached to the frame 36.

The illustrative embodiment of the invention having been described, its use and operation will now be explained. Assuming that work is to be operated upon for which the jack has not been adjusted, the shaft 28 is first raised, the wedge 104 being in the position in which it is illustrated in Fig. 1, to such a height that the abutment 22 cannot possibly engage the tread surface of the heel of a shoe to be jacked. At this time also the jacking spindle 26 is in its lowermost position, the abutment 24 being spaced substantially from the adjacent portion of the last. The shoe 15 is presented to the positioning fingers 50 and 52, toe foremost, causing the fingers to separate and to slide along the crease between the sole and the upper until their final position in the crease adjacent to the heel breast corners as determined 20 by the members 76 and 78 is reached. It is to be understood that at the time when the shoe is thus placed in the jack it is at the loading station of the machine where there is no operating instrumentality to interfere with the above-described movement of the shoe. With the shoe 25 thus supported by the fingers 50 and 52, it is pushed so as firmly to hold the heel breast against the members 76 and 78, thereby causing the longitudinal axis of the shoe to be aligned with that 30 of the jack. The forepart-engaging abutment 72 is now positioned, by making up the set screw 74, at such a height that the plane of the rand crease is perpendicular to the axis of rotation 35 of the jack which passes through the middle of the heel part of the shoe. It is now apparent that when the shoe is held in contact with the aforesaid positioning members it is definitely located heightwise and laterally by the fingers 50 and 52 and the abutment 72 and angularly by 40 the members 76 and 78. Moreover, all other shoes of the type for which the aforesaid adjustments have been made will be so positioned that the rand or rand crease always occupies the same 45 position. After the shoe has been thus positioned, the nut 92 is turned to bring the abutment 22 in proximity to the tread surface of the heel. The wedge 104 is then moved to the left from its position as illustrated in Fig. 1 to cause the abutment 22 to be pressed firmly into engagement with the heel. The shoe is then ready to 50 receive jacking pressure, which is imparted by raising the jacking spindle 26, thereby causing the spring 27 to be compressed after the clamping abutment 24 has come in contact with the heel part of the last opposite the abutment 22. Jacking pressure may be applied to the spindle 55 26 by any suitable means, preferably by the use of mechanism such as preferred to above and disclosed in the above-mentioned Letters Patent. 60 If the operating tools, the rand-burnishing tool and the indenting wheel, are not at such a height as to engage the portion of the heel to be operated upon when swung into engagement with it, they are first adjusted heightwise by 65 adjusting the position of the block 40 on the end of the arm 42. As the tools are swung toward the heel surface to be treated owing to the action of the spring 44, the guide 142 first engages the peripheral surface of the heel and causes the bearing member 122 to be swung until the indenting tool engages the heel surface, at which instant the wheel at the operating point has complete heightwise contact with the heel surface to be indented. At the same time the lip 144 of the 70 75

rand-burnishing tool 34 enters the rand crease and bears against the marginal portion of the rand. Owing to the obliquity of the member 39 with respect to the drive shaft 38 on which the frame 36 and associated parts are free to slide axially, one component of the pressure exerted by the member 39 against the frame 36 tends to cause the latter to be moved upwardly, whereby the pressure required to effect satisfactory burnishing of the rand is provided. The other component of the pressure of the member 39, namely that extending transversely with respect to the shaft 38, is utilized to force the operative surface of the indenting wheel 32 into the peripheral surface of the heel far enough to form the required indentations. As the shoe is moved to cause the point of operation of the tools to be transferred about the heel, the rand-burnishing tool 34 is oscillated rapidly owing to the rotation of the drive shaft 38, but the indenting wheel merely rolls idly in its bearing member 120 while swinging also about a tangent to its surface at the operating point as an axis owing to the coaction of the guide 142 which also rolls along the heel surface being operated upon but at a point remote from the operating point of the tool. At the conclusion of the indenting and burnishing operation the link 46 is moved outwardly of the machine by mechanism such, for example, as that described in the above-mentioned Letters Patent, to move the operating tools away from the shoe in preparation for the next movement of the jack carrier 16, which will bring another shoe into position to be operated upon.

While the present invention is concerned with an improved heel-burnishing and indenting device and an improved work jack which positions the shoe, by engaging the rand, relatively to a tool for operating on the rand itself, it is to be understood that the invention, in the indenting aspect, may have application to an indenting device to which the work is presented by hand, and that the invention in the work jack aspect may have application in a machine in which it is desired to jack a shoe so that the heel is located in predetermined relation with respect to a tool for operating upon any part or the whole of its peripheral surface.

Having thus described my invention, what I claim as new and desire to secure by Letters Patent of the United States is:

1. In a finishing machine, an indenting tool mounted for bodily swinging movement in order to allow complete heightwise contact between the heel surface to be indented and the face of the tool at the operating point, and means associated with said tool for controlling said swinging movement and mounted to engage a part of the surface to be indented.

2. In a finishing machine, an indenting tool having a curved operative surface, said tool being mounted to have limited tilting movement about an axis substantially tangential to its operative surface, means associated with said tool and actuated by engagement with a part of the heel surface to be indented for tilting said tool, and means for yieldingly holding said last-mentioned means against said heel surface.

3. In a finishing machine, an indenting tool, a bearing member rotatably supporting said tool, said bearing member being mounted to have a bodily swinging movement, means for urging said bearing member toward one extreme of its movement, and a guide associated with said tool adapt-

ed to engage a part of the surface to be indented thereby to control the position of the bearing member so as to insure complete heightwise contact between the tool and the surface.

4. In a finishing machine, an indenting wheel mounted to have limited tilting movement about an axis tangential to its face at the point of operation, means for urging said wheel toward one extreme position of its limited movement, and means for positioning said wheel to effect complete contact between the wheel and heel lengthwise thereof at the operating point.

5. In a heel finishing machine, a rotatably mounted indenting wheel having a peripheral operative surface, said wheel also being mounted for angular movement in order to allow complete heightwise contact between a heel surface to be indented and the operative face of the wheel at the operating point, and means responsive to pressure of the heel surface thereagainst for angularly moving said wheel.

6. In a finishing machine, a bearing member, an indenting tool journaled in said bearing member, a support for said bearing member, connections between said bearing member and support constructed and arranged to allow a limited swinging movement of said bearing member, and a guide mounted on said bearing member to engage the surface to be operated upon at a point in the plane of movement of said bearing member and spaced from the operating point of said indenting tool thereby to position the bearing member so as to effect complete contact between the tool and surface heightwise thereof.

7. In a finishing machine, a bearing member having an arcuate arm, an indenting wheel journaled in said bearing member, a support for said bearing member constructed and arranged to receive said arm whereby limited swinging movement of said bearing member is permitted in a plane including the axis of said wheel, means for yieldingly urging said bearing member toward one of its extreme positions, and a guide roll mounted on said bearing member and adapted to be actuated by a heel surface held in contact therewith thereby to position said bearing member so as to effect complete heightwise contact between the heel and the surface to be indented.

8. In a finishing machine, a bearing member having an arcuate support, means constructed and arranged to receive said support to allow limited swinging movement of said support about an axis at the center of curvature of said support, means for urging said bearing member toward one extreme of its limited movement, a ridged indenting tool journaled in said bearing member, the ridges of which tool are shaped with reference to the surface to be indented, and a guide carried by said support mounted to engage the said surface at a point included by an extension of the ridge of the tool surface at the operating point.

9. In a finishing machine, a support, an indenting tool mounted for movement with respect to said support about a tangent to the operative surface of the tool as an axis, a guide associated with said tool and mounted to engage the surface to be indented at a point on an element of the heel surface including the operating point of the tool and spaced therefrom, and means for holding said guide against the surface of the work being operated upon by the tool.

10. In a heel-finishing machine, an indenting wheel having a ridged surface the ridges of which are shaped heightwise with respect to the ele-

- ments of the peripheral heel surface to be operated upon, a bearing member in which said wheel is journaled, said member being mounted to swing about an axis substantially tangent to said wheel 5 at the operating point whereby said wheel may be angularly adjusted to effect complete heightwise contact between the heel surface to be indented and the ridge of the indenting wheel at the operating point, and a roll for angularly positioning said wheel the heel-engaging surface of which is intersected by that ridge of the indenting wheel when extended which passes through the operating point.
11. In a finishing machine, means for jacking the shoe, an indenting tool, said tool and jacking means being relatively movable to allow the point of operation of the tool on the heel to be transferred thereabout, said tool being mounted to tilt in a plane intersecting the heel surface and 15 extending heightwise thereof, said plane including an element of the tool at the operating point, and a guide actuated by engagement with the heel surface for positioning said tool thereby to effect complete heightwise contact between the heel and the operative face of the tool at the operating point.
12. In a finishing machine, means for jacking the shoe, an indenting tool, said jacking means and tool being relatively movable to allow the point of operation of the tool on the heel to be transferred thereabout, a support for the tool mounted to swing about an axis disposed substantially at the operating point of the tool to allow complete heightwise contact between the heel 20 and the operative face of the tool, and means carried by said support and actuated by engagement with a part of the heel surface for positioning said tool.
13. In a finishing machine, means for jacking a shoe, a rotatable indenting wheel, said wheel and jacking means being relatively movable whereby said wheel is caused to roll about a heel surface to be indented, said wheel normally being freely movable into complete heightwise contact with the heel surface at the operating point, and means responsive to pressure of the heel surface for positioning said wheel.
14. In a finishing machine, means for jacking a shoe, an indenting tool having a ridged periphery, said tool and jacking means being relatively movable whereby the point of operation of the tool on the heel is transferred thereabout, said indenting tool being mounted for bodily movement about a tangent to its periphery as an axis, and means for angularly positioning said tool bodily and having a work-engaging surface which is intersected by the ridge of the tool surface at the operating point when extended.
15. In a finishing machine, means for jacking a shoe, an indenting tool adapted to operate upon the peripheral surface of the heel of said shoe, said tool and said jacking means being relatively movable whereby the point of operation of the tool on the heel is progressively transferred thereabout, a bearing member constructed rotatably to support said indenting tool and mounted to swing about an axis substantially tangent to the indenting tool at the operating point, means actuated by engagement with the heel surface at a point spaced heightwise thereof from the operating point of the tool thereon for angularly positioning said bearing member, and means for yieldingly holding said last-mentioned means against the heel surface.
16. In a finishing machine, means for jacking a shoe, a support mounted for movement toward and away from said jacking means, an indenting wheel, a bearing member in which said indenting wheel is journaled, said member being mounted on said support to swing about an axis substantially tangential to the operative surface of the wheel, a roll mounted on said bearing member coaxially with respect to said indenting wheel for positioning said wheel by engagement with the heel surface at a point spaced from the operating point of the wheel, and yielding means for urging said roll against the heel surface.
17. In a heel-finishing machine, a tool for operating upon the peripheral surface of a heel, and shoe-jacking means mounted for movement relatively to the tool to cause the point of operation of the tool on the heel to be transferred thereabout in a path predetermined heightwise of the heel, said jacking means comprising positioning members shaped and arranged to engage the shoe 15 within the rand crease at opposite points adjacent to the heel thereby to position the heel laterally and heightwise with respect to the tool, an abutment, means for adjustably positioning said abutment in engagement with the tread surface of the 20 positioned heel, and means cooperating with said abutment for applying jacking pressure to the shoe.
18. In a heel-finishing machine, a tool for operating upon the peripheral surface of a heel, and shoe-jacking means mounted for movement relatively to the tool so as to cause the point of operation of the tool on the heel to be transferred thereabout in a path predetermined heightwise of the heel, said jacking means comprising positioning members shaped and arranged to engage the shoe 25 within the rand crease adjacent to the corners of the heel in order to position the heel part laterally and heightwise with respect to said tool, an abutment movable into engagement with the tread surface of the positioned heel, means for applying jacking pressure to the shoe, and means for supporting said abutment in adjusted position against the pressure of said last-mentioned means.
19. In a heel-finishing machine, a tool for operating upon the peripheral surface of a heel, and shoe-jacking means mounted for movement relatively to the tool to cause the point of operation of the tool upon the heel to be transferred thereabout in a path predetermined heightwise of the heel, said jacking means being constructed and arranged to engage the shoe within the rand crease adjacent to the heel thereby to position the heel part laterally and heightwise with respect to the tool and having a member for positioning the forepart by engagement with the tread surface thereof, an abutment mounted and arranged to be fixedly positioned in engagement with the tread surface of the positioned heel, and means 40 cooperating with said abutment for applying jacking pressure to the shoe.
20. In a heel-finishing machine, a tool for operating upon the rand of a heel, and shoe-jacking means mounted for movement relatively to the tool to cause the point of operation of the tool on the rand to be transferred thereabout, said jacking means comprising positioning members shaped and arranged to engage the shoe 45 within the rand crease adjacent to the heel at 50 opposite sides thereof, the rand-engaging surfaces of which members and the operating surface of said tool are disposed at substantially the same height, an abutment movable into engagement with the tread surface of the positioned heel, and means 55 cooperating with said abutment for applying jacking pressure to the shoe.
21. In a heel-finishing machine, a tool for operating upon the rand of a heel, and shoe-jacking means mounted for movement relatively to the tool to cause the point of operation of the tool on the rand to be transferred thereabout, said jacking means comprising positioning members shaped and arranged to engage the shoe 60 within the rand crease adjacent to the heel at 65 opposite sides thereof, the rand-engaging surfaces of which members and the operating surface of said tool are disposed at substantially the same height, an abutment movable into engagement with the tread surface of the positioned heel, and means 70 cooperating with said abutment for applying jacking pressure to the shoe.

- heel, and means cooperating with said abutment for applying jacking pressure to the shoe.
21. In a heel-finishing machine, a tool for operating upon the rand of a heel, and shoe-jacking means comprising cooperating positioning members shaped and arranged to engage the shoe at opposite sides within the rand crease adjacent to the heel thereby to position the heel laterally and heightwise, means for positioning the forepart of the shoe adapted to engage the tread surface of the sole, an abutment mounted for movement into engagement with the tread surface of the positioned heel, and means cooperating with said abutment for applying jacking pressure to the shoe.
22. In a heel-finishing machine, a tool for operating upon the rand of a heel, and shoe-jacking means mounted to rotate to cause the point of operation of the tool on the rand to be transferred thereabout and comprising positioning members mounted and arranged to engage the shoe at the tread surface of the forepart and to enter the rand crease at opposite sides of the shoe near the heel thereby to position the shoe so that the plane of the rand is perpendicular to the axis of the jacking means and at the same height as the tool, said jacking means also comprising cooperating clamping members for applying jacking pressure to the heel part of the shoe.
23. In a heel finishing machine, a tool for operating upon the rand of a heel, and shoe jacking means mounted to turn about an axis to cause the point of operation of the tool to be transferred about the rand of the shoe, said jacking means comprising members for positioning the shoe so that the plane of the rand crease is perpendicular to the axis of the jack, said members being mounted and arranged to engage the shoe at the marginal surface of the rand adjacent to the heel corners and at the tread surface of the forepart of the sole.
24. In a heel finishing machine, a tool for operating upon the rand of a heel, and shoe jacking means mounted to turn about an axis to cause the point of operation of the tool to be transferred about the rand of the shoe, said jacking

means comprising members shaped and arranged to enter the rand crease at opposite sides of the shoe near the corners of the heel thereby to position the heel laterally and heightwise with reference to said tool, and means mounted to engage the tread surface of the forepart of the sole for positioning the shoe held thereagainst so that the plane of its rand crease is perpendicular to the axis of rotation of said jacking means.

25. In a heel finishing machine, a tool for operating upon the rand of a heel, and shoe jacking means mounted to turn about an axis to cause the point of operation of the tool to be transferred about the rand of the shoe, said jacking means comprising members shaped and arranged to enter the rand crease at opposite sides of the shoe near the corners of the heel thereby to position the shoe laterally and heightwise with reference to said tool, and means mounted for adjustment heightwise with respect to said rand crease entering members and adapted to engage the tread surface of the forepart of the sole for positioning the shoe held thereagainst so that the plane of its rand crease is perpendicular to the axis of said jacking means.

26. In a heel finishing machine, a tool for operating upon the rand of a heel, and shoe jacking means mounted to turn about an axis to cause the point of operation of the tool to be transferred about the rand of the shoe, said jacking means comprising members shaped and arranged to enter the rand crease at opposite sides of the shoe near the corners of the heel thereby to position the heel laterally and heightwise with reference to said tool, means mounted to engage the tread surface of the forepart of the sole for positioning the shoe held thereagainst so that its rand crease is perpendicular to the axis of said jacking means, and a member associated with each of said positioning members mounted to engage the heel breast at each side thereof thereby to align the longitudinal axis of the shoe with said forepart positioning member.

HENRY B. GREENOUGH.
